CLAIM

The ornamental design for a passenger service unit, as shown and described.

DESCRIPTION

FIG. 1 is a perspective view of the passenger service unit showing our new design;

FIG. 2 is a front view of the passenger service unit of FIG. 1;

FIG. 3 is a right view of the passenger service unit of FIG. 1;

FIG. 4 is a left view of the passenger service unit of FIG. 1; FIG. 5 is a bottom view of the passenger service unit of FIG. 1;

FIG. 6 is a close-up perspective view of the passenger service unit of FIG. 1;

FIG. 7 is a close-up front view of the passenger service unit of FIG. 1; and,

FIG. 8 is a close-up bottom view of the passenger service unit of FIG. 1.

The evenly-spaced broken lines in FIGS. 1-6 depict environmental structure that forms no part of the claimed design. The additional evenly-spaced broken lines in FIGS. 5 and 8 showing internal elements depict portions of the passenger service unit that form no part of the claimed design. The dash-dot-dash broken lines in FIGS. 1-2 and 5-8 are for the purpose of annotating the close-up views and form no part of the claimed design. The passenger service unit is shown with a symbolic break in its length. The appearance of any portion of the article after the break lines, as well as the break lines themselves, form no part of the claimed design.

1 Claim, 8 Drawing Sheets
